UNITED STATES PATENT OFFICE.

JANE B. MOORE, OF COVINGTON, KENTUCKY.

DESIGN FOR A PIN OR SIMILAR ARTICLE.

SPECIFICATION forming part of Design No. 29,119, dated August 2, 1898.

Application filed April 18, 1898. Serial No. 678,081. Term of patent 7 years.

To all whom it may concern:

Be it known that I, JANE B. MOORE, residing at Covington, in the county of Kenton and State of Kentucky, have invented and 5 produced a new and original Design for a Pin or Similar Article, of which the following is a specification.

The object of my invention is to produce a design adapted to form an appropriate 10 symbol for the State of Kentucky.

Reference being had to the accompanying drawings, making a part of this application, Figure 1 is a plan view of a design for a pin or similar article. Fig. 2 is a central vertical 15 section of the same.

The leading features of my design are represented upon a pin or similar article, and consist of an ear of corn A, embraced by the nut or corn crackers B. I have shown the ear with the husks partly stripped back, showing the kernels and a ribbon in the foreground.

C represents the ordinary pin for attachment to the clothing.

Having described my invention, I claim— 25
The design for a pin, or similar article, substantially as herein shown and described.

In testimony whereof I have hereunto set my hand.

JANE B. MOORE.
